EYE MOUNTING FOR DOLLS

Nunzio Paganello, Brooklyn, N. Y.

Application April 20, 1935, Serial No. 17,421

5 Claims. (Cl. 46—169)

This invention relates to improvements in eye mountings for dolls, and more particularly to a structure wherein the eyeballs frictionally engage the walls of the sockets and are yieldingly supported therein.

One object of the invention is to provide an eye mounting having relatively few parts, of simple and inexpensive construction, in which the eyeballs may be readily and quickly positioned in their sockets without the exercise of a high degree of skilled labor.

Another object of the invention is to provide a guide for directing the eye carrying shaft, prior to the positioning of the eyeballs in the sockets, which guide is permanently secured to the doll's head immediately after the head is molded and before the head is painted or completely finished.

Another object is to provide a guide and retainer which is malleable so as to be bent in one direction after the eyeballs and its shaft are positioned, thereby preventing the mounting from becoming unintentionally displaced, which guide may also be bent in a reverse direction to permit the removal of the eyeballs and shaft.

Another object is to provide certain improvements in the form, construction and arrangement of the parts whereby the above named and other objects may effectively be attained.

A practical embodiment of my invention is represented in the accompanying drawing, in which:

Fig. 1 represents a vertical section of a doll's head looking toward the front interior wall and showing my improved eye mounting applied thereto;

Fig. 2 represents a vertical section taken in the plane of the line II—II of Fig. 1, looking in the direction of the arrows;

Fig. 3 represents a horizontal section taken in the plane of the line III—III of Fig. 1, looking in the direction of the arrows;

Fig. 4 represents a detail vertical section similar to that shown in Fig. 2, showing the parts in another position; and

Fig. 5 represents a perspective view of the guide and retainer.

The doll's head is denoted by 1 and the front wall by 2. The front wall 2 is provided with the usual spaced eye sockets 3, 4 properly located with respect to the nose and other molded features of the head. The eye sockets are formed with the usual interior curve adapted to receive the semi-spherical eyes 5, 6 of any well-known and approved construction. The eye carrying device comprises a horizontally disposed shaft 7,

upon the opposite ends of which are secured the semi-spherical eyes 5, 6, which may be adjusted rotatably and longitudinally thereon in any manner well-known in the art.

A counter-balance 8 is fixed to the shaft 7 by means of depending arms 9, 10 spaced apart and adjacent the eyes 5, 6. The arms 9, 10 are also extended above the shaft 7 to form stops 12, 13 which serve to limit the rotary movement of the shaft 7 in one direction. The eyes 5, 6 are held in engagement with their respective sockets by means of an element 11 formed of a relatively flat thin strip of sheet metal having one end fixed to the interior wall of the head by any well-known and approved fastening means, in the present instance, I employ a bifurcated rivet 14, the head 15 of which being cemented or otherwise secured in a recess 16 formed in the head. The prongs 17 of the rivet are disposed to extend through a hole 18 in the end of the element 11 and be bent in opposite directions to retain the element in position on the head. The element 11 is arranged in the head so as to extend downwardly between the arms 9, 10 and stops 12, 13. The lower end of the element 11 is developed into an elongated recess 19 which is arranged to engage the shaft 7 between the arms 9, 10 so that the eyes 5, 6 will contact with the sockets and oscillate therein. This elongated recess 19 is designed to allow the shaft 7 to be positioned therein and compensate for slight differences in the position of the sockets in the head, as well as allow a vertical movement of the shaft.

In order that the shaft 7 may receive proper and sufficient resiliency to maintain the eyes in their sockets so that they will roll easily and smoothly, I provide a fairly stiff flat strip of resilient metal 20, one end of which is secured in contact with the fixed end of the element 11, while the other end is arranged to engage the free upwardly turned end 21 of the element 11. This upwardly turned end 21 of the element is spaced rearwardly from and directly in vertical alinement with the rear of the recess 19. Thus, it will be seen that the continuous pressure applied to the element 11 by the resilient strip 20 will be transferred through the wall of the recess 19 to the shaft 7 which, in turn, holds the eyes in contact with their respective sockets. To prevent the displacement of the eyes in their sockets, such as might be caused by suddenly jarring the head, or by the eyes being pushed inwardly from the front, I provide a member having two arms 22 formed of wire or other similar malleable metal spaced apart and arranged to extend rear-

wardly and upwardly from the interior wall of the head.

The member is preferably formed of a single piece of wire bent at 23 to form a bight which is fixed in a recess 24 in the front interior wall of the head substantially to the rear of the nose portion, by cement or other cementitious material. The arms 22 are curved so as to be substantially concentric with and spaced from the shaft 7 when the eyes are positioned in their sockets. The distance between the ends of the curved arms and the upper interior edges 25 of each of the sockets is less than the distance between the outer surface of the eyes and the shaft 7, so that the eyes cannot unintentionally leave the sockets entirely, but will always be so positioned that they may be returned to the sockets by the resilient strip 20 and element 11, when displaced.

20 In Fig. 4 I have shown the manner of assembling the eye shaft and eyes in their sockets, and, it will be seen that the ends of the arms 22 are spaced from the interior walls of the head, so that the shaft may pass therebetween and 25 still leave a sufficient distance for the exterior surface of the eyes to pass the upper edges 25 of the sockets when they are moved downwardly in position to enter the sockets. In the initial movement of the shaft in assembling the eyes 30 in the head, the shaft will first be brought into contact with the curved exterior edges of the arms 22 and between the curved lower end 26 of the element 11, as shown in dotted outline in Fig. 4. In the further upward movement the 35 shaft will ride on the curved exterior edges of the arms 22 until it passes from the ends thereof. The shaft 7 is then brought downwardly along the interior edges of the curved arms until it is located in the recess 19 of the element 11, in 40 which position the eyes 5, 6 will enter their respective sockets 3, 4 in the head. After the eyes are located in their sockets, the free ends of the curved arms 22 are slightly bent toward the front to the position shown in Figs. 1, 2, and 45 3, in which position the shaft cannot unintentionally be removed from the arms nor the eyes permanently displaced from their sockets.

If it is desired to remove the shaft and eyes from the head, it is only necessary to bend the 50 upper ends of the curved arms 22 rearwardly so as to open the space between the interior wall of the head and the arms, as shown in Fig. 4, through which opening the shaft can be passed.

It is understood that various changes may be 55 resorted to in the form, construction and arrangement of the several parts without departing from the spirit and scope of my invention; and hence, I do not intend to be limited to the details herein shown and described except as 60 they may be included in the claims.

What I claim is:

1. In combination with a doll's head having eye sockets therein, a horizontally disposed shaft, semi-spherical eyes secured on said shaft in position to oscillate in said sockets, a resilient element having its upper end fixed in the head and the lower end being provided with an elongated recess adapted to engage the shaft for yieldingly holding the eyes in their sockets and adapted to 65 permit longitudinal adjustment of the shaft and eyes, said lower end of the element below said recess being curved outwardly from the head, and an independent means for guiding the shaft 70 from becoming unintentionally displaced.

under the curved end of the element and the eyes into operative position when being assembled, said means being normally spaced from the shaft when in operative position and also adapted to be bent inwardly to prevent the shaft and eyes 5 from becoming unintentionally displaced.

2. In combination with a doll's head having eye sockets therein, a horizontally disposed shaft, semi-spherical eyes secured on said shaft in position to oscillate in said sockets, a resilient element having its upper end fixed to the head and its lower end curved outwardly and free to engage the shaft for yieldingly holding the eyes in their sockets, and means comprising a piece of wire bent to form a bight secured to the head 15 and having upwardly and outwardly curved arms spaced apart from said bight for guiding the shaft under the curved free end of the element and the eyes into operative position when being assembled.

3. In combination with a doll's head having eye sockets therein, a horizontally disposed shaft, semi-spherical eyes secured on said shaft in position to oscillate in said sockets, a resilient element having its upper end fixed to the head and 25 its lower end curved outwardly and free to engage the shaft for yieldingly holding the eyes in their sockets, and means comprising a piece of wire bent to form a bight secured to the head and having upwardly and outwardly curved arms 30 spaced apart from said bight for guiding the shaft under the curved free end of the element and the eyes into operative position when being assembled, said arms being adapted to be bent inwardly to prevent the shaft and eyes from 35 becoming unintentionally displaced.

4. In combination with a doll's head having eye sockets therein, a horizontally disposed shaft, semi-spherical eyes secured on said shaft in position to oscillate in said sockets, a resilient element having its upper end fixed to the head and 40 its lower end curved outwardly and free to engage the shaft for yieldingly holding the eyes in their sockets, and means comprising a piece of wire bent to form a bight secured to the head 45 and having upwardly and outwardly curved arms spaced apart from said bight for guiding the shaft under the curved free end of the element and the eyes into operative position when being assembled, the interior of said arms being substantially concentric with and normally spaced from the shaft when in operative position.

5. In combination with a doll's head having eye sockets therein, a horizontally disposed shaft, semi-spherical eyes secured on said shaft in position to oscillate in said sockets, a resilient element having its upper end fixed to the head and 55 its lower end curved outwardly and free to engage the shaft for yieldingly holding the eyes in their sockets, and means comprising a piece 60 of wire bent to form a bight secured to the head and having upwardly and outwardly curved arms spaced apart from said bight and disposed to straddle the lower end of said resilient element 65 for guiding the shaft and eyes into operative position when being assembled, the interior of said arms being substantially concentric with and normally spaced from the shaft when in operative position, said arms also being adapted to be bent inwardly to prevent the shaft and eyes 70 from becoming unintentionally displaced.

NUNZIO PAGANELLO.
